US0D1049488S

(12) **United States Design Patent** (10) Patent No.: **US D1,049,488 S**
(45) Date of Patent: ** Oct. 29, 2024

(54) **EPILATOR**

(71) Applicant: **Braun GmbH**, Kronberg (DE)

(72) Inventors: **Björn Kling**, Glashütten (DE); **Gregor Ptak**, Frankfurt (DE); **Robert Schmidt**, Liederbach am Taunus (DE); **Wolfgang Stegmann**, Frankfurt (DE)

(73) Assignee: **Braun GMBH**, Kronberg (DE)

(**) Term: **15 Years**

(21) Appl. No.: **29/849,819**

(22) Filed: **Aug. 15, 2022**
